UNITED STATES PATENT OFFICE.

JOHN S. CAMERON, OF EVANSVILLE, INDIANA, ASSIGNOR OF ONE-HALF TO ADDISON W. IGLEHEART, OF SAME PLACE.

GAGE FOR FLOURING-ROLLS, &c.

SPECIFICATION forming part of Letters Patent No. 537,017, dated April 9, 1895.

Application filed July 26, 1894. Serial No. 518,607. (No model.)

To all whom it may concern:

Be it known that I, JOHN S. CAMERON, a citizen of the United States, residing at Evansville, in the county of Vanderburg and State 5 of Indiana, have invented certain new and useful Improvements in Gages for Flouring and other Rolls; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 This invention is directed to devices for gaging the relative positions of the rolls of roller mills, and has for its object the production of a simple but efficient gage for this purpose, which can be applied with equal 20 facility to the under side or to the top of the rolls, and whether the latter are at rest or in motion, with a view to determining the degree of vertical adjustability requisite for paralleling the same.

25 The nature of my invention will become apparent from a reading of the subjoined description when taken in connection with the accompanying drawings, which form a part of this specification, and in which—

30 Figure 1 is a plan view of my improved roll gage. Fig. 2 is a side elevation of the same. Fig. 3 is a vertical, central, sectional view. Fig. 4 is a front elevation showing the indicators in a different position. Fig. 5 is a view 35 showing a pair of rolls with my improved gage applied to the under side thereof, and Fig. 6 is a similar view showing the gage applied to the upper side or top of said rolls.

Like letters of reference denote like parts 40 in the several figures of the drawings.

Referring to the drawings by letter A denotes my improved gage, and B B' are the rolls which latter are shown out of parallelism.

45 The gage consists essentially of two rods a a which are centrally reduced at a' to give a clearance for the scrapers which are employed in connection with smooth rolls, and which rods are also recessed on their inner 50 sides to reduce the weight and add rigidity. The surfaces indicated at a² a² are planed

true and in practice engage the peripheries of a pair of rolls at four points as will be presently more fully referred to. The rods are each centrally apertured at a³ a³, for connection with a king bolt c which is provided with the reduced screw threaded ends c' c' for said apertures, nuts d d being employed to complete the connection. The rods are permitted to turn on said bolt, and for this 55 reason the bolt is provided with collars c² c² which abut against the inner sides of the rods, and the nuts are screwed up against the shoulders c³ formed by the reduced ends c', in order to prevent the binding of the rods 60 between the collars and nuts. In practice these rods are brought against the peripheries of a pair of rolls, and by reason of the loose connection, the surfaces a² all contact with said peripheries whether the rolls are in 65 parallelism or not, as will be understood by reference to Figs. 5 and 6. The conformity of the rods with the relative position of the rolls is accomplished automatically, in that any pressure on the king bolt will cause the 70 rods, if the rolls are out of parallelism, to turn on said bolt until all four surfaces contact with the peripheries of the rolls.

Any means for manipulating the gage may be employed, but I prefer to use a handle e 80 which is arranged parallel with the rods and connected centrally to the king bolt by a vertical post or arm e'. The connection of the handle with the gage being exactly central of the latter, it is evident that the gage is very 85 sensitive, and that the slightest variation from parallelism of the rolls will be indicated, inasmuch as the movements or adjustability of the two rods will be simultaneous, one being depressed and the other raised until the contact is made at the four points.

In order to adapt the gage for application to the upper side as well as the underside of the rolls, I provide an indicator which is capable of being secured to the rods in two positions, and which will show the degree of adjustment requisite for paralleling the rolls. Said indicator consists of two arms f f, which are bent inward at one end, f', to span the ends of the rods, and bent outward at their 100 other ends to form indicator fingers f² f² which are arranged parallel to each other and

extend in a direction opposite to the bent ends f' . In the ends of each of the rods to which the indicator is secured are threaded perforations g, g', g^2 , which are located respectively 5 in the side, end and top thereof, the side perforation g receiving a thumb-screw h which is first passed through a slot f^3 in the end f' of one of the indicator arms, the connection of the other arm being made with the other rod 10 in a similar manner. This connection forms a pivotal joint which enables the indicator to be turned and secured in alignment with the rods as shown in Fig. 5, or at right angles thereto as shown in Fig. 6. $h' h'$ are thumb 15 screws which are passed through perforations $f^4 f^4$ in the arms adjacent to the bent ends f' , and screwed into the apertures g' to secure the indicator in alignment with the rods, or into the apertures g^2 to secure the indicator 20 at right angles to said rods. The indicator fingers are loosely secured together by means of a bolt i which is passed through a slot i' in one of said fingers and screwed into an aperture i^2 in the other finger, this connection permitting each finger to follow the movement of the rod to which it is rigidly connected. The connection of the indicator with the rods, which permits of their relative position being 25 changed, is for the purpose of enabling the operator to apply the gage to the under side or to the upper side of the rolls, as conditions permit, or in order to verify the indications. The gage aside from this feature, may be applied to rolls when at rest, or in motion, preferably at the latter time, as I have found that 30 there is always a perceptible difference in the relative positions of the rolls when idle as compared with the active periods.

In practicing my invention, the indicator is 35 secured in the position required for the application, and the handle is brought against the periphery of the rolls, and slight upward or downward pressure as the case may be, being given the rods, are caused to adjust them-

45 selves to the positions of the rolls, the positions, and consequently the degree of adjustment required, being shown by the indicators. This application of the gage may be made from above or below the rolls, it being preferred to make the double test in order to 50 prove the indication.

The gage is as a whole very simple but yet effective. It is durable, light of weight, and may be cheaply produced and is very accurate in practice.

55 I claim as my invention—

1. A gage for the rolls of roller mills consisting of two rods loosely connected together, and adapted for contact at four points on said rods, and an indicator adapted to be removable 60 secured to said rods in different positions for the purpose set forth.

2. A gage for the rolls of roller mills consisting of two rods centrally connected but independently movable and adapted for contact at four points on said rods, and an indicator consisting of two arms each pivotally connected to one end of each arm and adapted 65 to be secured in different positions with reference to the rods, said arms being loosely 70 connected together, all as and for the purposes set forth.

3. A gage for the rolls of roller mills consisting of two rods connected together centrally by a king bolt, but independently movable, the indicator consisting of the two arms having the bent portions and the indicator fingers, apertures in the arms and ends of the rods, and thumb screws for securing said rods 75 and indicators in different relative positions, 80 for the purpose set forth.

In testimony whereof I affix my signature in presence of two witnesses.

JNO. S. CAMERON.
